UNITED STATES PATENT OFFICE.

ARTHUR G. BOOZER, OF PROVIDENCE, RHODE ISLAND, ASSIGNOR OF ONE-HALF TO
GEORGE HILL, OF TUCAPAU, SOUTH CAROLINA.

STRIPPING MECHANISM FOR CARDING-MACHINES.

1,327,696.

Specification of Letters Patent.

Patented Jan. 13, 1920.

Application filed April 12, 1918. Serial No. 228,263.

To all whom it may concern:

Be it known that I, ARTHUR G. BOOZER, a citizen of the United States, and resident of Providence, county of Providence, and 5 State of Rhode Island, have invented certain new and useful Improvements in Stripping Mechanism for Carding-Machines, of which the following is a specification.

My invention relates to certain improvements in pneumatic or so called vacuum strippers for card-clothing of the cylinders of carding machines, one of the objects of 10 the invention being to provide means for stripping either one or all of the card-clothed cylinders during the productive 15 operation of the carding machine. Another object of my invention is to provide simple and effective means for stripping the card-clothed cylinders, which is not liable to be 20 clogged by the fibers, neps, dust and foreign matter that pass through the suction nozzles, or are present in the vicinity of the carding machine. Another object of this 25 invention is to provide stripping mechanism for carding machines in which several suction nozzles are alined to extend across the card clothed cylinder, the nozzles being rendered effective in non-consecutive order, whereby each nozzle acts upon a non-adjacent 30 portion of the circumference of a rotary cylinder.

My invention is distinguished from the prior state of the art in that there is present a transverse series of suction nozzles maintained adjacent to the teeth of the card-clothing of a cylinder or flat, the pipes or conduits associated therewith each having an independently actuated hinged valve, such valve and its actuating means being 35 such as to obviate the liability of becoming 40 inoperative by the strippings, and in that the suction nozzles are rendered operative in non-consecutive order to be effective upon disassociated or non-adjacent portions of 45 the clothing of the cylinder to be stripped.

My invention is designed to provide stripping mechanism of the suction type which will not be clogged by the fiber, neps, dust and foreign articles that are drawn into the 50 nozzles and are present in a carding room, and to place the operating mechanism so as to avoid undue encroachment upon the

aisle space and to simplify the construction of the parts and operating means therefor, as will be hereinafter set forth.

55

In the accompanying drawings, Figure I is a side elevation, partly in section, of a suction nozzle, its valve and valve operating cam, constructed to accord with my invention. Fig. II is a perspective view of the 60 valve. Fig. III is a plan view of the suction nozzle. Fig. IV is a diagrammatic view showing an arrangement of the cams which operate the valves of the suction nozzles. Fig. V is a view showing the transverse relation of the suction nozzles and a shaft 65 having thereon cams to one of the cylinders of a carding machine, and Fig. VI is a side elevation showing several applications of the strippers to the cylinders of a carding 70 machine.

Referring to the drawings which illustrate a preferred embodiment of my invention 10 designates a suction nozzle which is attached to or formed integral with a 75 flanged member 11, which member may be a casting, and the nozzle may be made of sheet metal with a hollow end that fits into the open end of the flanged member 11, which may be tubular or rectangular. The 80 nozzle 10 has sides which diverge from the point of support to a point near the opening 12, which is a narrow slit formed by cutting away at a bevel the top and bottom plates. The suction nozzles of the 85 shape shown are placed along side of each other, and the suction openings will be maintained in line with the terminal portions of the teeth of the card-clothing, of the cylinders or flats.

90

The suction nozzles are connected to conduits or pipes 13 that have end flanges with apertures to receive bolts or screws, for attaching the nozzles to said section of the suction system, and the conduit 13 to a valve 95 carrying section. The conduits 13 may be of any suitable shape and carry a lug or lugs 14 to receive a bar 15, for connecting the sections to the frame of a carding machine, and adjacent to the lugs 14 there is 100 an apertured projection 16 for a spring. The lugs and projections 16 may be the terminal portions of attached bands, and the screw or bolt receiving apertures may be

spaced to admit of the section 13 being coupled to the section of the suction conduit having a valve, and to the nozzle to properly position the nozzle relative to the teeth of the card clothing. The supporting rod 15 between lugs 14 may carry spacing tubes or sleeves and the ends of the rods engage with the side frames of the carding machine.

The flanged ends of the conduits or pipes 13 are coupled by means of screws or bolts to one end of a section 17, that has associated therewith a hinged valve, such section 17 being connected in any suitable manner with a pipe 18, which leads to a receiving chamber and a vacuum or suction pump, located at a central station where the strips removed by the nozzles are separated from the neps, dust and other waste. It will be understood that the pipes 18 may be a part of an overhead vacuum or suction system, or may be supported upon the floor or alongside of the frame of the carding machine.

The valved section 17 is constructed to be coupled to the pipes 13 and 19, and an intermediate portion of the section 17 has parallel flat sides and a side at right angles thereto and opposite the last mentioned side there is an opening and means for attaching to the section a hinged or oscillatory valve 20. The section 17 may be a one piece casting or it may be made in sections, and adjacent to the upper end of the opening are apertured lugs or bosses to receive a removable pinte 21 upon which the valve is oscillated, and below the lower portion of the opening there is a transverse stop 22, against which projections 23 and 24 will engage. The valve 20, is of such construction that when moved in either direction it serves as a closure for the opening through the section to which it is attached. As shown by Figs. I and II, the valve 20 has an inclined face 20' which terminates above a straight-across face 24' that abuts against the section 17 opposite the opening therethrough, and when the valve is moved to admit air into the nozzle there will be no obstructions and the stripings will be carried by suction to a receiving chamber. When the valve is positioned to cut off the suction from the nozzle, should there be any leakage it will be stopped by the stripings drawn into the tube, which stripings will be released when the position of the valve is changed. The hinged valve may be readily removed from the section 17 by taking out the pinte 21. The hinged valve 20 has attached thereto or formed integral therewith an arm 25, that carries a roller or wear piece 26 which is held against the face of a cam or recessed disk 27 by a spring 28, the ends of the spring being attached to the arm 25 and to the lug 16.

The disks or cams 27 are mounted on a shaft 28, that is driven by a belt that en-

gages a fixed pulley adjacent to which is an idle pulley, and suitable means may be provided for shifting the drive belt to the fixed or driving pulley when a cut off valve in the conduit is turned to establish communication with a suction pump. In practice when a carding machine is provided with, for instance, eight nozzles there will be a like number of cams 27 which may be arranged as shown by Fig. IV, the recesses being positioned so that the valves 20 will not be operated successively, but by preference in the order indicated by the small numerals 1 to 8 inclusive, (see Figs. I and IV of the drawings,) the object of such arrangement being to avoid bringing adjacent nozzles successively into operation, as that would be liable to produce in the sliver or product of the carding machine thin places. When a cylinder or flat is stripped the suction is cut off by operating a valve (not shown) attached to the pipe 18.

The stripping device hereinbefore described may be applied to either one or two places to strip the main cylinder, and is applicable to the doffer cylinder, the flats and to the licker-in, several applications being shown by Fig. VI of the drawings, and where a single carding machine is provided with several series of suction nozzles or stripping mechanism of the construction hereinbefore described, each stripping mechanism may be connected to a suction pipe common to the particular carding machine, and such pipes will be connected to a suction pipe that is common to several or all the carding machines in the carding room of the mill.

The invention set forth in the claims obviates the objection to rotary valve mechanism, which has heretofore been applied to stripping mechanism for carding machines, and I consider rotary valves objectionable, as in use the stripings have a tendency to mass between rotary surfaces and form a packing or dense mass that will stop the rotation of contacting parts. I am aware that it has been proposed to provide an apparatus for cleaning the cylinders of carding machines by means of suction nozzles which extend over the entire width of the cylinder to be stripped, pipes from the nozzles being connected to a plate having a series of concentric apertures, and a suction pipe having an end which is moved to cover and uncover successively the apertures, the movable end of the suction pipe being operated by a pawl and ratchet mechanism. The construction of the mechanism and arrangement of the parts is such as not to avoid the objection to rotary valve mechanism, and is also objectionable in that its construction is such as to encroach to a prohibitive extent upon the aisle space between the carding machine.

I claim:—

1. In a vacuum stripping mechanism for carding machines, a plurality of stripping nozzles, a suction conduit common to each of the stripping nozzles, pipes connecting the nozzles to the conduit, valves maintained by the pipes, and actuating means for the valves operating individual valves in non-successive order to establish communication 10 between non-adjacent nozzles and the conduit.

2. In a vacuum stripping mechanism for carding machines, a plurality of suction nozzles maintained to extend across the face 15 of a card clothed cylinder, a suction conduit common to each nozzle, pipes between the nozzles and the conduit, valves mounted for oscillation in each of the pipes and means for oscillating the valves in non-successive 20 order; whereby non-adjacent portions of the cylinder will be stripped in non-consecutive progression.

3. In card stripping mechanism, a nozzle attached to a pipe, a suction conduit to 25 which the pipe is connected, a valve maintained in hinged engagement with the pipe, and constructed to prevent ingress of air through the nozzle and the ingress of air through the pipe to the conduit, and means 30 for oscillating the valve.

4. In card stripping mechanism, a suction nozzle maintained with its inlet opening adjacent to the card-clothing which it is desired to strip, a pipe associated with the 35 nozzle and with a conduit that is connected with means for producing a partial vacuum therein, a valve maintained in oscillatory engagement with the pipe, and means comprising a spring and a rotated disk having a 40 recess in its periphery for actuating the valve.

5. In card stripping mechanism, a plurality of suction nozzles maintained to extend across the card-clothing which it is desired 45 to strip, pipes for connecting each of the nozzles to a conduit, a hinged valve for each nozzle, a spring for each valve which tends to hold the valve to which it is attached in position to cut off communication between 50 a nozzle and a conduit in which a partial vacuum is maintained, and rotary members

having surface depressions to permit movement of the valves.

6. In card stripping mechanism, a suction nozzle, a suction pipe having an opening to receive a hinged valve, a valve maintained in hinged engagement with the suction pipe and provided with a portion that is inclined to provide a diagonal cut-off between the nozzle and means for producing a suction in 60 the pipe, and a segmental portion for closing the suction pipe against the entrance of air through the opening through the suction pipe, and means for actuating the valve.

7. In card stripping mechanism, a suction 65 nozzle comprising top, bottom and side members which are associated so that the bottom member extends beyond the top member to provide a suction opening between the sides and beyond the top member of the nozzle, a pipe for connecting the suction nozzle with a suction conduit, a hinged valve maintained by the pipe and means for oscillating the valve.

8. In stripping mechanism for card cloth- 75 ing of carding machines, a plurality of suction nozzles maintained to extend across the clothing to be stripped, pipes for each of the nozzles, a conduit that communicates with each of the pipes and with means for producing a partial vacuum therein, hinged valves associated with each of the pipes between the nozzles and the conduit the valves having arms to which springs are attached for moving the arms toward valve actuating 80 means, and valve actuating means comprising a driven shaft having thereon a plurality of disks with peripheral recesses which are positioned so that adjacent valves 85 will not be successively actuated.

9. In combination with card stripping mechanism, a nozzle, a suction conduit, a pipe having a valve carrying section which connects the nozzle with the suction conduit, an oscillatory valve hinged to the valve 95 carrying section and provided with a face which when serving as a cut-off extends at an inclination across the valve carrying section, and means for holding the valve in position to cut-off the nozzle from the suc- 100 tion conduit.

ARTHUR G. BOOZER.
